(57) **CLAIM**

The ornamental design for a ball, as shown and described.

DESCRIPTION

FIG. 1 is a front view of the ball showing my new design;

FIG. 2 is a right perspective view thereof;

FIG. 3 is a left perspective view thereof;

FIG. 4 is a right view thereof;

FIG. 5 is a left view thereof;

FIG. 6 is a top view thereof; and,

FIG. 7 is a plan view of the four panel shapes incorporated in the design, shown separately for clarity.

The design consists of 32 panels incorporating two of panel shape A, and ten each of panel shapes B, C and D.

It is understood that the portions of the ball in between the panels, which are not illustrated in the drawings form no part of the claimed design.
